UNITED STATES PATENT OFFICE.

JAMES H. WAGENHORST, OF JACKSON, MICHIGAN.

BATTERY-JAR MANDREL.

Application filed October 31, 1921, Serial No. 511,859. Renewed May 27, 1926.

This invention relates generally to battery jar making machines and more particularly to a novel construction of mandrel used in said machine. The object of the invention 5 is to provide a simple and efficient construction of mandrel upon which can be formed a complete battery jar composed of a plurality of cells and embodying an outer case or wall and subdividing partitions. Another 10 object of the invention is to provide a mandrel of this character in which the strips of rubber which form the partitions can be quickly and easily inserted preparatory to being surrounded by the side portions of the 15 jar, and another object is to provide a mandrel embodying these features which will also position the supporting feet or lugs which are employed in the bottoms of the cells. Another object of the invention is to 20 provide a mandrel of the kind referred to from which the vulcanized battery jar can be quickly and easily removed.

With these various objects in view the invention consists in the novel features of construction hereinafter fully described and pointed out in the claims.

In the drawings forming a part of this specification Fig. 1 is a perspective view of a mandrel embodying one form of my invention; Fig. 2 is an end view of the same illustrating the manner of separating the sections of the mandrel preparatory to inserting the rubber partitioning strips, the mandrel being positioned upon a support having oppositely disposed inclined portions to permit the angular separation of the mandrel sections; Fig. 3 is an inverted bottom plan view of the mandrel; Fig. 4 is a section on the line 4-4 of Fig. 3; Fig. 5 is a section 30 on the line 5-5 of Fig. 2 and Fig. 6 is a section on the line 6-6 of Fig. 2; Fig. 7 is an inverted perspective view showing a slightly modified form of hinge connection; Fig. 8 is a detail view of a slightly modified form 40 of hinge; Fig. 9 is a sectional perspective illustrating the major portion of a complete battery jar formed upon the mandrel; Fig. 10 is a perspective view of a modified form 45 of battery jar; Fig. 11 is a detail sectional view illustrating the manner of connecting the handle to the end of the jar; Fig. 12 is a view showing a slight modification in the connection of the handle and Fig. 13 is a

plan view of another modified form of jar, it being possible to shape all of the afore- 55 said jars upon the mandrel constituting the subject matter of this application.

In the practical embodiment of my invention, I provide a mandrel composed of a central section A and side sections B, these 60 mandrels being cast hollow as shown in Figs. 4, 5 and 6 and having a central reinforcing web C. Each section is given the proper dimensional contour and is preferably enveloped by a thin coating of lead as shown 65 at D. This thin coating of lead is capable of receiving a high polish which in connection with the physical and chemical properties of lead will prevent the vulcanized rubber adhering thereto. The mandrel sections 70 being of cast metal will have abundant strength to resist all pressures placed thereon and thereby prevent the thin lead covering from being injured or distorted. Each 75 battery section is formed with notches or recesses E in the closed ends thereof to receive the lugs or foot pieces E' which are to be vulcanized to the bottom E² of the battery jar E³.

Each mandrel section is formed with a 80 base F at the open end thereof and in addition thereto link members G are formed upon the lower ends of the section A and link members H upon the lower ends of the sections B, these link members being apertured as shown at I to receive the pivotal bolt K when the sections are placed together 85 in their proper positions and the eyes I brought into register. By this means the sections of the mandrel are pivotally connected together, and the adjacent flanges at the sides of the central and end sections are of such dimensions that they will contact with or engage one another as most clearly shown in Figs. 1 and 4 when the mandrel is 90 set in position ready to receive the strip of rubber thereabout which shall constitute the sides and ends of the jar. The mandrels A, B and C are spaced apart a definite distance as indicated at L for the purpose of 95 receiving the partitioning strips E⁴ therebetween and in order to facilitate the insertion of these partitioning strips I pivotally connect the sections of the mandrel together as previously described. As a first step in the 100 operation of forming the jar, I move the

section or mandrel upon a support which has a flat central portion A' and oppositely disposed inclined portions B'; and when the section or mandrel is moved upon this portion of the support, the end sections B swing away from the central section A as most clearly shown in Fig. 2 providing an angular space L' into which the partitioning strips E⁴ can be quickly and easily inserted, the edges of the strips resting upon the base flanges of the central member A. Then when the mandrel is moved to another portion A² of the support, the sections B will be brought back to their true perpendicular positions such as shown in Figs. 1 and 4, inasmuch as all of the bases rest upon the continuous horizontal portion A² of the support.

The lugs or foot pieces E' may be inserted either before or after the partitioning strips are set in place.

After the lugs and the partitioning strips have been set in place, then the bottom of the jar is placed upon the closed ends of the mandrel and which in the illustration are the upper ends thereof. The strip of rubber which is to form the sides and ends of the jar is then folded around the mandrel and the pressure applied thereto so as to initially unite the sides and ends of the jar with the bottom thereof and also with the partitioning strips and lugs.

The mandrel with the jar thus formed thereon is then placed in a vulcanizer and the jar vulcanized; after which the mandrel with the vulcanized jar thereon is removed from the vulcanizer and the vulcanized jar stripped therefrom. This can be accomplished in various ways, either by applying hooks to the ends of the jar or push rods may be passed up between cut-out portions of the bases as shown at L² in Fig. 8, the pivot bolts in this instance being made short instead of extending the full width of the mandrel as shown in Fig. 3. It will also be noted by reference to Fig. 8 that the link members G and H are formed with bosses G' and H' surrounding the openings I, which bosses can have their faces machined so as to provide an accurate fit between these parts. In this way, accuracy of position of the cast metal parts can be obtained.

After the battery jar has been formed upon the mandrel, vulcanized and stripped therefrom, the mandrel is ready for use again and the various operations are repeatedly carried on as previously described.

By means of a mandrel of this kind I am able to form a complete battery jar comprising a plurality of cells separated from each other by means of partitions, the ends of which are thoroughly united by vulcanization with the side walls of the battery jar. The interior of the battery jar will, of course, be determined by the shaping and

size of the mandrel and the exterior will be determined by enveloping wings or plates of the battery jar making machine.

In Figs. 10 and 13 I have shown different exterior designs which can be formed, enveloping wings or plates being cut to produce such designs, such embossing being employed preferably for the purpose of reducing weight.

In Figs. 10 and 11 I have illustrated a novel form of handle M having counterbored openings M' so that when the handles M are pressed against the strip of rubber N which constitutes the end of the box a portion of the rubber will be forced through these counterbored openings and in vulcanization the handles will be quickly connected to the ends of the jar. It will also be noted that the ends of the jar are slightly elevated at the center as shown at N', thereby protecting the handles from contact with the electrolyte, as in handling the jars the electrolyte is liable to slop over and may come in contact with the metallic handles of the jar, but by elevating the end portions of the center this liability is considerably reduced. In Fig. 12 I have shown a handle which is connected to the elevated end portion N' by means of screws O'. These screws can be inserted in the soft rubber before vulcanization and can be removed after vulcanization and then screwed back again to connect the handle to the end of the jar. This feature of my invention is disclosed and claimed in my pending application for battery jars and method of making the same, Serial No. 114,522, filed June 8, 1926.

It will thus be seen that I provide a simple and efficient construction of mandrel capable of carrying out all of the objects herein referred to.

Having thus described my invention, what I claim is:

1. A mandrel for making a multiple cell battery jar, comprising a plurality of sections, each having a base, said bases being connected to each other.

2. A mandrel for making a multiple cell battery jar, comprising a plurality of sections each having a base, said bases being pivotally connected to each other.

3. A mandrel for making a multiple cell battery jar comprising a plurality of sections each having a laterally extending base, said bases being pivotally connected to each other.

4. A mandrel for making a multiple cell battery jar, comprising a plurality of sections, said sections being capable of separation to receive the partition strips therebetween, and also capable of reverse movement to hold said strips therebetween while the mandrel as a whole is enveloped.

5. A mandrel for making a multiple cell

- battery jar comprising a plurality of sections pivotally connected and capable of separation to receive the partition strips therebetween, and capable of reverse movement to progressively grip said strip, and bring said sections into alignment to be enveloped as a whole.
6. A mandrel for making a multiple cell battery jar comprising a plurality of sections pivotally connected together and capable of angular separation to receive the partition strips therebetween, and capable of a reverse movement to grip said strips and align said sections to be enveloped.
- 10 7. A mandrel for making a multiple cell battery jar comprising a plurality of sections pivotally connected together and capable of angular separation to receive the partition strips therebetween, and capable of a reverse movement to grip said strips and
- 15 20

align said sections to be enveloped in combination with means for effecting said separation and alignment.

8. A mandrel for making a multiple cell battery jar comprising a plurality of sections pivotally connected together and of such construction as to maintain definite spaced relation to one another when in alignment and capable of being moved out of alignment to separate said sections to receive the partition strips therebetween.

25 9. The combination with a mandrel composed of a plurality of sections hinged together, of a support composed of two parts, one to hold said mandrel sections in alignment and the other to separate said sections, when said sections rest thereon.

30 35 In testimony whereof, I hereunto affix my signature.

JAMES H. WAGENHORST.
